Charles A. Dearborn Inventor
By his Attorney, *Smith, B. & D.*

UNITED STATES PATENT OFFICE.

CHARLES A. DEARBORN, OF NEW YORK, N. Y.

ADJUSTING MEANS FOR SEWING-MACHINE WORK SUPPORTS.

Application filed May 17, 1921. Serial No. 470,287.

To all whom it may concern:

Be it known that I, CHARLES A. DEARBORN, a citizen of the United States, residing in the borough of Manhattan, city, county, and State of New York, have invented certain new and useful Improvements in Adjusting Means for Sewing-Machine Work Supports, of which the following is a specification.

10 The present invention relates to improved means for conveniently and accurately adjusting the pivoted work support of a blind stitch sewing machine of the type illustrated in Patent No. 814,026 granted to me March 15 6th, 1906. In this type of sewing machine, the work is passed over a pivotally mounted work support or table that holds the work in engagement with the under face of a stationary presser foot in proper relation to 20 the feeding and stitch forming mechanisms. It is essential in this type of machine to maintain an accurate adjustment of the work support with relation to the stationary presser foot and because of the varying 25 character of some classes of work, it is sometimes necessary for the operator to change the adjustment of the work support in the midst of a sewing operation. The purpose of the present invention is to afford convenient 30 means for rapidly and accurately correcting the adjustment of the work support. To this end, the present invention consists of a hand operated adjusting screw mounted in the machine frame and engaging a part projecting 35 from the pivoted work support and a spring actuated pin or dog mounted in the machine frame and engaging a recessed collar upon the adjusting screw to retain the screw in the desired position against accidental displacement.

In order that the invention may be fully understood, it will now be described with reference to the accompanying drawing. In said drawing

45 Figure 1 is a side elevation of the forward part of a blind stitch sewing machine having my improved adjusting devices applied thereto.

Figure 2 is a vertical, sectional view of 50 a part of the same on a slightly larger scale, showing the details of said devices.

1 is the base of the sewing machine, from 55 which rises the auxiliary arm 30 in the upper end of which is pivoted at 34 the horizontal, forwardly extending work supporting frame 40. Surrounding the pivot shaft

34 is a torsion spring whose opposite ends engage respectively the flange 40a of the frame 40 and the hook rod 46 which passes through the machine arm 30 and has its 60 threaded, forward end engaged by a wing nut 48.

The work support 40 has an integral, downwardly projecting arm 41 which is engaged at its lower end by an adjusting screw 49 which is threaded through the auxiliary arm 30 and is provided at its exposed outer end with a milled head 50 by which the screw 49 can be readily adjusted for causing the work support 40 to move upon its pivot. 70 Adjacent to the milled hand wheel 50 is a rigidly attached crown wheel or collar 55 formed in its edge with a series of slightly indented, curved recesses 56 which are engaged by the curved outer end 57 of the 75 spring actuated pin or dog 58. The pin or dog 58 is seated in a cylindrical bore 59 formed in the machine arm 30 above and parallel with the threaded socket of the screw 49. The pin 58 is formed with a rearwardly projecting guide rod 60 which guides in the cylindrical bore 61 of the hollow screw 62 threaded in the rear end of the socket 59 and held in the desired adjusted position by a lock nut 63. An expansion 80 spiral spring 65 surrounds the guide rod 60 and is confined between the adjustable hollow screw 62 and the shoulder at the rear of the pin or dog 58. The adjustment of screw 62 regulates the spring pressure of the 85 pin or dog 58 in its engagement with the crown wheel 55. It will be observed that, while the machine is in operation, the operator can easily and quickly turn the adjusting screw 49 for raising or lowering the 90 work support to obtain the desired relationship between the work and the needle. The spring actuated pin or dog 58 retains the adjusting screw in the desired set position and prevents accidental disarrangement of the adjustment while, at the same 100 time, the engagement of the pin in the rounded recesses of the crown wheel is such that the screw can be readily adjusted with but slight pressure of the operator's hand. 105

I claim:—

1. The combination of a machine frame, with a spring sustained work support pivotally mounted upon said frame, a rigid arm projecting from said work support, an adjusting screw mounted in said frame and engaging said rigid arm for limiting the 110

- action of the spring and moving the work support against the spring action, a crown-shaped collar upon said adjusting screw having an inwardly presented recessed edge, 5 and a spring actuated pin or dog mounted in said frame parallel with said adjusting screw and engaging the recessed edge of said collar for retaining the screw in the desired adjusted position.
- 10 2. The combination of a sewing machine frame with a spring-sustained work support pivotally mounted upon said frame, an arm projecting from said work support, an adjusting screw threaded in said frame and engaging said arm, a recessed collar carried by said adjusting screw, a pin or dog mounted in a recess in said frame and engaging said recessed collar, said pin or dog having a rearwardly projecting guide pin, a hollow screw threaded in the frame recess in rear of 20 said pin or dog and engaging said guide pin and a spring surrounding said guide pin and confined between said pin or dog and said hollow screw.

CHARLES A. DEARBORN.
